Primary Examiner — Paula Greene*(74) Attorney, Agent, or Firm* — James A. Quinton**CLAIM**

I claim the ornamental design for a door handle, as shown and described.

DESCRIPTION

FIG. 1 is a perspective view of a door handle according to the invention.

FIG. 2 is a front view of a door handle according to the invention.

FIG. 3 is a right side view of a door handle according to the invention, the left side being a mirror image thereof.

FIG. 4 is a top plain view of a door handle according to the invention.

FIG. 5 is a bottom view of a door handle according to the invention; and,

FIG. 6 is a rear view of a door handle according to the invention.

The broken lines form no part of the claimed design.
